MANUALLY OPERATED WALL MOUNTED
CAN OPENER

Theodorus Cornelis Marie van der Kroft, Valkenswaard,
Netherlands, assignor to Van Elderen's Metaalwaren-
fabriek "Brabantia" N.V., Aalst, Netherlands

Filed Feb. 22, 1971, Ser. No. 117,865

Term of patent 14 years

Int. Cl. D7—04

U.S. Cl. D8—37

FIG. 1

FIG. 2

FIG. 3

FIG. 4

FIG. 1 is a front elevational view of a manually operated wall mounted can opener showing my new design;

FIG. 2 is a side elevational view thereof;

FIG. 3 is a top plan view thereof; and

FIG. 4 is a bottom plan view thereof.

The back surface of the can opener is flat and unornamented.

I claim:

The ornamental design for a manually operated wall mounted can opener, as shown and described.
